UNITED STATES PATENT OFFICE.

WALTER JESSE ELLWOOD, OF SIOUX FALLS, SOUTH DAKOTA.

DESIGN FOR A BADGE OR THE LIKE.

Application filed December 24, 1925. Serial No. 15,843. Term of patent 14 years.

To all whom it may concern:

Be it known that I, WALTER J. ELLWOOD, a citizen of the United States, residing at Sioux Falls, in the county of Minnehaha and State of South Dakota, have invented a new, original, and ornamental Design for Badges or the like, of which the following is a specification, reference being had to the accompanying drawing, forming part thereof.

I claim:

The ornamental design for a badge or the like, as shown.

WALTER JESSE ELLWOOD.
